UNITED STATES PATENT OFFICE.

JOHN F. DANIELS, OF DECATUR, ILLINOIS.

STAND AND TANK FOR VAPOR-STOVES.

SPECIFICATION forming part of Letters Patent No. 269,391, dated December 19, 1882.

Application filed September 29, 1882. (No model.)

To all whom it may concern:

Be it known that I, JOHN F. DANIELS, a resident of the city of Decatur, county of Macon, and State of Illinois, have invented certain new and useful Improvements in Vapor-Stoves, of which the following is a specification.

My invention relates to "tanks" and "stands" for vapor-stoves; and it consists in a stand **T** shaped in ground plan and provided with receptacles for various articles. The body or part corresponding to the top bar of a **T** is provided with a shallow sink over its entire surface, and with a series of depressions under the burners. The part of the stand corresponding with the leg or upright of a **T** is covered with and acts as a support for a folding leaf, and both the body and leg are provided with suitable doors and drawers. Attached to the body of the stand is a back board provided with a box for the fluid-tank, said box having an automatically-closing lid and a convex bottom.

In the drawings accompanying and forming a part of this specification, Figure 1 is a perspective view of my device. Fig. 2 is a sectional view of the oil or fluid tank contained in the box to the rear of the back board, *c*, of the stand; and Fig. 3 is a section of said box.

a is the tank. *c* is the back board. *s* is the back, *k* the ends, *o o* the bottom, and *b* the lid, of the box that contains the fluid-tank. *m m* is the **T**-shaped stand, provided with receptacles, as indicated. *e* is the shallow sink, provided with depressions *g g g*, which indicate the position of the burners on pipe *d*. *f f f* is the ledge that forms the sink *e*, above mentioned. *h* is a table-extension provided with folding leaf *i*. *t* is the hollow screw in tank *a*, provided with holes *u u'*, that admit air and permit the fluid to escape. *v v* are shoulders on tank *a*, that close holes *u u'* when screw *t* is turned down sufficiently to bring said holes in contact with said shoulders.

The lid *b* is provided with spring *p*, that holds said lid tightly closed. Bottom *o o* of the box containing the oil-tank is inclined, as shown in Fig. 3, and made to fit tightly around pipe *d* to prevent the fluid from running down the supply-pipe should the tank overflow while

being filled. The depressions *g g g* are located under the burners, and receive and hold all droppings therefrom. In case of a serious leak in the burners the ledge *f f f* will prevent 55 the fluid from spreading.

Leaf *i* may be used as a table, there being sufficient room to seat a person in the angles of the stand; or said leaf may be folded to economize space and permit free access to the 60 drawers in front.

The entire device may be made on the "knock-down" principle, so that it may be taken apart and packed for shipping.

A grate provided with suitable legs will be 65 set over each burner to support the articles to be heated.

Any number of burners from one to four may be used, and the device made to conform thereto.

Lid *b* is made to fit close to the box, and in case of an accident while filling the tank will immediately swing shut and smother the fire.

The stand and box may be made of any fire-proof material, and may be variously ornamented.

I claim—

1. Box *s o k k*, located in the rear of back board, *c*, provided with lid *b*, that closes automatically, and inclined bottom *o o*, that prevents the fluid from running down the supply-pipe, as shown and described.

2. The combination, in a stand and tank for vapor-burners, of **T**-shaped stand *m m*, provided with receptacles, sink *e*, table *h i*, and tank-box *s o k b*, as and for the purpose set forth.

3. The combination, with stand *m m* and tank-box *s o k b*, of folding leaf *i*, forming a 90 table when extended, and permitting free access to the receptacles in the front of the stand when folded, as shown and described.

4. The combination, in a stand and tank for vapor-stoves, of stand *m m*, table *h i*, sink *e*, 95 elongated tank *a*, provided with hollow screw *t*, and box *s o k k*, with its lid *b* on back board, *c*, all as shown and described.

JOHN F. DANIELS.
